UNITED STATES PATENT OFFICE

121,522

DESIGN FOR A DECORATIVE ELECTRIC
LAMP BODY OR SIMILAR ARTICLE

John Petry, Long Island City, N. Y.

Application April 26, 1940, Serial No. 91,961

Term of patent 7 years

To all whom it may concern:

Be it known that John Petry, a citizen of the United States and resident of Long Island City, in the county of Queens and State of New York, has invented a new, original and ornamental Design for Decorative Electric Lamp Body or Similar Article, of which the following is a specification, reference being had to the accompanying drawing, forming part thereof, in which

Fig. 1 is a front elevational view of a decorative electric lamp body or similar article showing my new design;

Figs. 2 and 3 are side and bottom views, respectively, thereof.

I claim:

The ornamental design for a decorative electric lamp body or similar article, as shown.

JOHN PETRY.
